UNITED STATES PATENT OFFICE

129,465

DESIGN FOR A RANGE

Elmer D. Pellegrin, Woodstock, Ill., assignor to
Geo. D. Roper Corporation, Rockford, Ill., a
corporation of Illinois

Application March 24, 1941, Serial No. 99,806

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Range, of which the following is a specification, reference being had to the accompanying drawing, forming part thereof.

In the drawing:

The figure is a perspective view of a range showing my new design, the end which does not show in this view being like the other end illustrated. The small circles appearing on the front

panels indicate the locations for handle attachments and gas cock and oven regulator knobs, which are omitted. The four elongated openings appearing in the upper front panel indicate the locations of drip pan handles, which are also omitted. The dotted lines on the cooking top indicate the position of the lids over the burners.

The dominant features of the design reside in the portions shown in full lines.

I claim:

The ornamental design for a range, substantially as shown and described.

ELMER D. PELLEGRIN.
